MATCHBOX

Frank L. Sinks, Wadsworth, Ohio, assignor to
The Ohio Match Company, Wadsworth, Ohio,
a corporation of Delaware

Application July 25, 1951, Serial No. 16,012

Term of patent 14 years

(Cl. D48—29)

To all whom it may concern:

Be it known that I, Frank L. Sinks, a citizen of the United States of America, residing at Wadsworth, in the county of Medina and State of Ohio, have invented a new, original, and ornamental Design for a Match Box, of which the following is a specification, reference being had to the accompanying drawing, forming a part hereof.

The single figure of the drawing is a perspective view of a match box showing my new design.

The dominant features of my design are shown in the drawing in solid lines and are characterized by providing the striking surface of the match box as a definite stripe having a marbleized, veined or striated effect.

The side of the box opposite that shown in the drawing is conventional.

I claim:

The ornamental design for a matchbox, as shown and described.

FRANK L. SINKS.
